UNITED STATES PATENT OFFICE.

ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

BRAKE SUPPORTING AND LEVELING DEVICE.

1,339,416.

Specification of Letters Patent. Patented May 11, 1920.

Application filed April 22, 1918. Serial No. 229,937.

To all whom it may concern:

Be it known that I, ARMAND H. PEYCKE, a citizen of the United States, and resident of Chicago, in the county of Cook and State 5 of Illinois, have invented certain new and useful Improvements in Brake Supporting and Leveling Devices, of which the following is a specification.

This invention relates to a brake supporting and leveling device.

One of the objects of this invention is to simplify and improve brake supporting and leveling devices, and to combine parts in a novel manner for reducing the amount of 15 necessary material.

Another object is to provide an improved combination of brake supporting and leveling devices and safety bar hangers, adapted to meet the various requirements for successful operation.

These and other objects are accomplished by means of the arrangement disclosed by the accompanying sheet of drawings, in which,

25 Figure 1 is a fragmentary side elevation of a railway car truck, embodying my invention.

Fig. 2 is a fragmentary end view of the supporting and leveling device means.

30 Fig. 3 is a detail sectional view, taken in the plane of line 3—3 of Fig. 1.

Fig. 4 is a fragmentary side elevation of 35 a railway car truck, embodying a modification of my invention, and

Fig. 5 is a detail partial end elevation of the same.

The various novel features of my invention will be apparent from the following description and drawings and will be particularly pointed out in the appended claims.

40 Referring first to Figs. 1, 2 and 3 of the drawings, it will be noted that I have shown my invention as applied to a railway car truck, including a spring plank 10, under 45 which is mounted a safety bar 11, which extends to opposite sides of the spring plank underneath brake beams, including a compression member 12, a tension member 13 and a fulcrum 14, extending between 50 said compression and tension members. The function of the safety bar 11, is to catch the brake beam and prevent the latter from falling to the ground in the event that it becomes detached from its normal hangings.

55 The safety bar 11 is supported in two brack-

ets 15, which are provided with spaced legs, having apertures therein, for the reception of the safety bar. These brackets preferably are secured to the spring plank, and interposed between the inner legs of the 60 brackets 15, there is secured to the safety bar a double spring clip 16, the ends of which engage the inner legs of the bracket 15 for positively locking the safety bar against longitudinal movement.

65 Formed integrally with the bracket 15 in each case, is a leveling member 17, preferably of spring material, said member extending over the brake beam and terminating in a loop 18 in which a balance hanger 70 or link 19 is pivotally connected by a pin or other pivotal connection 20. The lower end of the hanger 19 in each case is pivotally connected to the outer end of the fulcrum 14, whereby the brake beam is main- 75 tained in a balanced condition so that the brake shoes, carried by heads mounted on the brake beams will be maintained in concentricity with respect to the braking surfaces of the associated wheels 21. This 80 spring leveling device 17 permits the necessary movement in a vertical direction, in accordance with operating conditions, and at the same time properly supports the brake beam in the manner hereinabove men- 85 tioned.

85 Referring to Figs. 4 and 5 wherein I show the preferred embodiment of this invention, it will be noted that the safety bar 22 is hung in apertured brackets 23, said brackets 90 23 being formed by bending the material back on itself and providing the upper end of one leg with a hooked portion 24, overhanging a flange, in each case, of the spring plank 25, the brackets, in addition being 95 otherwise secured to the spring plank by rivets 26. The lower ends of the brackets are formed by upsetting the strip material to form a head 27, broadened out to give considerable bearing surface for the safety 100 bar 22. The safety bar in this case is provided with two spring clips 28, each of which engages its corresponding bracket 23 to prevent longitudinal movement of the safety bar. Formed integrally with each of 105 the brackets 23 is an overhanging leveling member 29, preferably of spring material connected to the brake beam 30, in the same manner as described in connection with the arrangement disclosed in Fig. 1. The func- 110

1339 416

tions and operation of the arrangement disclosed in Figs. 4 and 5 are the same as the arrangement disclosed in the other figures of the drawing.

5 Where a single central safety bar is used the resilient leveling device also may be arranged centrally. If two safety bars are used, one at each side of the truck, the spring leveling device may be offset having 10 its outer end in each case terminate centrally with respect to the brake beam.

It is evident that there may be various other modifications of my invention and it is my intention to cover all such modifications, 15 which do not involve a departure from the spirit and scope of the following claims.

I claim:

1. In brake mechanism, the combination 20 of a brake beam, a rigid safety bar underlying the beam, and separate means for supporting said safety bar and having a resilient portion operatively connected to said brake beam.

2. In brake mechanism, the combination 25 of a brake beam, a rigid safety bar for the beam, and a combined safety bar hanger and brake beam leveling device associated with the safety bar and brake beam.

3. In brake mechanism, the combination 30 of a brake beam, a rigid safety bar therefor, separate means for supporting said safety bar and extending into the proximity of said brake beam, and a supporting connection between said brake beam and extending 35 portion of said means.

4. In brake mechanism, the combination 40 of a truss brake beam, a safety bar therefor, a member forming a hanger for said safety bar and also having a portion extending over said brake beam, and a hanger

connecting said overhanging portion and the tension portion of said brake beam for maintaining the latter in balanced condition.

5. In brake mechanism, the combination 45 of a truss brake beam, a safety bar therefor, a member forming a hanger for said safety bar and also having a resilient member extending over the brake beam, and a hanger connecting said overhanging portion and the tension rod portion of said brake beam 50 for maintaining the latter in balanced condition.

6. In brake mechanism, the combination 55 of a spring plank, a member secured thereto having a bracket portion and a supporting portion, a safety bar carried by said bracket portion, a brake beam overlying said safety bar, and a hanger connecting said brake beam and supporting portion.

7. In brake mechanism, the combination 60 of a brake beam, a rigid safety bar therefor, a member supporting said safety bar and terminating at a point adjacent the brake beam, and a connection between said member and brake beam.

8. In brake mechanism, the combination 65 of a brake beam, a movably mounted safety bar therefor, a member having a bracket portion for supporting said safety bar, means normally preventing movement of 70 said safety bar, said member being operatively connected to said brake beam for maintaining the latter in balanced condition.

Signed at Chicago, Illinois, this 16th day of April, 1918.

ARMAND H. PEYCKE.
